BLISTER PACKAGE FOR A MEDICAL INSTRUMENT

James L. Armentrout, South Pasadena, and Pierre Vanat, Glendale, Calif., assignors, by mesne assignments, to American Hospital Supply Corporation, a corporation of Illinois

Filed Dec. 19, 1966, Ser. No. 5,106

Term of patent 14 years

(Cl. D9—192)

FIG. 1.

FIG. 2.

FIG. 3.

FIG. 4.

FIGURE 1 is a side elevational view of a blister package for a medical instrument showing our new design;

FIGURE 2 is a top plan view;

FIGURE 3 is an elevational view looking from the left of FIGURE 1; and

FIGURE 4 is an elevational view looking from the right of FIGURE 1.

The dotted line showing of a hypodermic syringe encased in the blister package for a medical instrument, is for illustrative purposes only.

We claim:

The ornamental design for a blister package for a medical instrument, as shown and described.
